UNITED STATES PATENT OFFICE

2,630,229

TRACTOR DRAWBAR, CONNECTING LINK,
GREASE GUN, AND OIL CAN CARRYING
KIT

Edwin F. Wick, Princeton, Wis.

Application June 29, 1950, Serial No. 171,023

2 Claims. (Cl. 211—87)

1

This invention relates to containers attached to tractors and the like for carrying tools and other attachments, and in particular a vertically disposed container having drawbar carrying elements therein with grease gun and oil can retaining elements carried by the ends thereof.

The purpose of this invention is to provide a tool carrying kit that may readily be mounted on a fender of a tractor by which continuously used tools are readily accessible.

In the conventional tractor it is difficult to find a convenient location for storing a drawbar and connecting link when these parts are not in use and with this thought in mind this invention contemplates an elongated vertically disposed kit or carrier in which a drawbar and connecting link may be retained and which is also provided with means for carrying a grease gun and oil can.

The object of this invention is, therefore to provide a tool carrying kit for tractors and the like that is so constructed that it may readily be mounted on a fender of a tractor without interfering with the general use of the tractor.

Another object of the invention is to provide a tool carrying kit for tractors that may be permanently mounted on tractors now in use without changing the design or arrangements of the parts thereof.

A further object of the invention is to provide a tool carrying kit for tractors and the like which is of a simple and economical construction.

Other features and advantages of the invention will appear from the following description taken in connection with the drawing wherein:

Figure 1 is a side elevational view illustrating the kit installed on the left rear fender of a tractor with parts of the tractor omitted.

Figure 2 is a similar view of the kit on an enlarged scale showing a front elevation thereof and illustrating the grease gun and oil can in dotted lines.

Figure 3 is an end elevational view of the kit looking toward the oil can carrying socket end thereof.

Figure 4 is also an end elevational view looking toward the opposite end and showing parts broken away illustrating the construction of the lower end of the kit.

Figure 5 is a plan view of the kit with the tools and other parts omitted.

Referring now to the drawing wherein like reference characters denote corresponding parts the improved tool carrying kit of this invention includes a vertically disposed rectangular shaped casing 10 having a drawbar retaining bracket 11

2

in the upper end and having a ring 12 with a spring clip 13 on the outer surface of one end and an oil can retaining socket 14 on the outer surface of the opposite end.

5 The casing 10 is provided with a front wall 15, a rear wall 16, end walls 17 and 18 and a bottom 19.

The upper end of the rear wall 16 is provided with a strap 20 and the strap is provided with a 10 bolt hole 21. The strap extends at an angle to compensate for the sloping upper surface of a fender 22 so that the strap fits snugly upon the upper surface of the fender.

The lower end 23 of the rear wall 16 extends 15 beyond the bottom 19 and the extending end is provided with a bolt hole 24 that is positioned to receive a bolt 25 positioned in a rivet hole provided in the fender.

The lower end or bottom 19 of the casing is 20 provided with a drain hole 26 as shown in Figure 4 to prevent water accumulating in the casing.

The outer surface of the oil can holding socket 14 is provided with a bracket 27 having an opening 28 therethrough through which a handle 29 25 of an oil can 30, as indicated in dotted lines in Figure 2, extends to prevent the handle swinging outwardly to interfere with the general use of the tractor.

With the parts arranged in this manner the 30 drawbar, as indicated by the numeral 31 is placed in the casing and with the upper part of the drawbar extended through the bracket 11 the lower end 32 extends through the drain opening 26 in the bottom 19. The connecting link as indicated by the numeral 33 is positioned in the outer part of the container.

An oil can 30 is positioned in the socket 14 and the grease gun 34 is inserted through the upper band 12 with the lower end thereof 40 snapped into the spring clip 13.

It will be understood that modifications may be made in the design and arrangements of the parts without departing from the spirit of the invention.

45 What is claimed is:

1. A tool carrying kit for tractors comprising an elongated vertically disposed casing having a bottom with a centrally disposed opening therein and having an open upper end, said casing 50 having a strap with a bolt hole therein extended at a rearwardly inclined angle from the upper end and having an extension with a bolt hole therein depending from the lower end, and a bracket positioned in a corner of the upper end 55 of the casing adapted to retain a drawbar in

position therein with an end of the drawbar extending through said opening in the bottom of the casing.

2. A tool carrying kit for tractors comprising an elongated vertically disposed casing rectangular shaped in cross section having front, rear and end walls with a bottom having a centrally disposed opening therein and in which the upper end is open, said rear wall having a strap with a bolt hole therein extended at a rearwardly inclined angle from the upper end and having an extension with a bolt hole therein depending from the lower end, and an L-shaped bracket positioned in a corner of the upper end of the casing adapted to retain a drawbar in position 15 therein with an end of the drawbar extended

through the opening in the bottom of the casing.
